UNITED STATES PATENT OFFICE.

CHARLES B. ROYAL, OF OAK PARK, ILLINOIS.

CONTROLLING MECHANISM FOR FIRE-BOX DOORS.

Application filed October 8, 1923. Serial No. 667,427.

To all whom it may concern:

Be it known that I, CHARLES B. ROYAL, a citizen of the United States, residing at Oak Park, in the county of Cook and State of Illinois, have invented a new and useful Improvement in Controlling Mechanism for Fire-Box Doors, of which the following is a specification.

My invention relates, more particularly, 10 though not exclusively, to locomotive fire-boxes provided with mechanism for actuating the fuel doors thereof; and my objects, generally stated, are to provide improvements in structures of this character as 15 hitherto provided, to the end, and more particularly, that the controlling device for the door-operating mechanism, while being readily accessible for the most convenient operation, will be removed from a position 20 in which it obstructs the free action of the fireman in moving about on the platform in front of the fire-box; to provide a novel, simple and automatic control for fluid-pressure-operated door-actuating mechanism; 25 and other objects as will be manifest from the following description.

Referring to the accompanying drawings:

Figure 1 is a face view of the fuel-door-equipped portion of a locomotive fire-box 30 provided with fluid-pressure-operated door-operating mechanism, a portion only of which is illustrated, embodying my invention, the structure being viewed at the line 1 on Fig. 2 in the direction of the arrow. Figure 2 is a view in side elevation of the structure shown in Fig. 1, the front wall of the fire-box being shown in section, and the view being taken at the line 2 on Fig. 1 and viewed in the direction of the arrow. Figure 40 3 is a section taken at the line 3 on Fig. 1 and viewed in the direction of the arrow. Figure 4 is a view in vertical sectional elevation of the platform of the locomotive in front of the fire-box of Figs. 1 and 2 and of another portion of the door-actuating mechanism, the valve thereof being shown in the normal position of the mechanism in which the door is closed. Figure 5 is a broken, similar view of the valve device of 45 Fig. 4, showing it in the position it assumes when manually operated to effect the opening of the door. Figure 6 is a section taken at the irregular line 6—6 on Fig. 4 and viewed in the direction of the arrow. Figure 50 7 is a view in side elevation of the front portion of the locomotive fire-box and platform

of Fig. 1, with certain parts thereof shown in section, and of the door actuating mechanism of the preceding figures. Figure 8 is a plan view of the structure shown in Fig. 7. 60 Figure 9 is a view in elevation, partly sectional, of the fluid-pressure-operated piston and cylinder device forming a part of the door-actuating mechanism, the section being taken at the line 9 on Fig. 10 and viewed in 65 the direction of the arrow. Figure 10 is a section taken at the line 10 on Fig. 9 and viewed in the direction of the arrow; and Figure 11, a broken sectional view of the device of Figs. 9 and 10, the section being 70 taken at the line 11 on Fig. 9 and viewed in the direction of the arrow.

Referring to the particular construction shown, the rear end wall of a locomotive fire-box is represented at 12 and the deck 75 extending therefrom and on which the fireman stands in stoking the fire-box, at 13. The opening through which the fuel is introduced into the fire-box is represented at 14, this opening, which is located in the rear 80 end 12 of the fire-box, having a door shown as of the sectional type and involving upper and lower sections 15 and 16 pivoted, as represented, respectively, at 17 and 18, to the frame 14^a of the door opening 14, the 85 section 15, which is heavier than the section 16, swinging upwardly and the section 16 swinging downwardly in accordance with practice well known in the art. The section 15, adjacent its pivot 17, is pivotally connected with the upper end of a link 19, as represented at 20, the lower end of this link being pivotally connected with one end of a lever 21, as represented at 22, this lever being pivoted between its ends to the frame 90 14^a, as represented at 21^a, and pivotally connected at its other end, as represented at 23, to the lower end of a link 24, the upper end of which is pivotally connected, as indicated at 25, with the door section 16 adjacent the 95 pivot 18 thereof. The door sections are thus operatively connected to move in unison, but in opposite directions, when force is applied thereto as hereinafter described.

The door sections 15 and 16 are represented as actuated through the medium of a link 26, which is pivotally connected at its upper end, with the pivot 20, the lower end of this link being pivotally connected, at 28, with the upper end of a piston 29 operating 105 in a cylinder 30 rigidly secured to the door frame 14^a. The cylinder shown and which,

with the piston 29, forms a part of the fluid-pressure-operated door-actuating mechanism, contains, in a wall thereof, a passage 31 forming a primary exhaust passage which opens into the cylinder 30 above the upper edge of its upwardly concaved bottom surface 32 and communicates with a chamber 33 in the cylinder wall, into which chamber a pipe 34, leading from a controlling valve-device hereinafter described, opens, the pipe 34 preferably comprising a flexible pipe section 34^a to permit the valved controlling device to be installed at any desired location. The cylinder 30 is provided with a combined inlet and supplementary exhaust port 35, which opens into the interior of the cylinder at the upper edge of its concave portion 32, and communicates with a passage 36 which opens into a passage 38 communicating at its opposite ends with chambers 37 and 39; a passage 40 leading from the chamber 39 into the passage 31, and a passage 37^a, leading from the chamber 37 to the chamber 33. Communication between passage 37^a and chamber 37 is controlled by a check valve 41 which permits flow of fluid pressure through passage 37^a, 38 and 36 and thence to the bottom of the cylinder and below the piston 29, but prevents flow of pressure through passage 38 to passage 37^a. The chamber 39 is equipped with a needle valve 42 for controlling the flow of the exhaustive fluid-pressure from the cylinder through passages 36, 38, chamber 39 and passages 40 and 31 to pipe 34.

The pipe 34 leads downwardly and through the deck 13 to the device hereinbefore referred to for controlling the actuation of the above described piston and cylinder mechanism, this device, shown located beneath the deck, comprising a housing 43 rigidly secured in an opening 44 in the deck 13, with its top, plate-like, portion 45 pivoted to the body of the housing, as represented at 46, and forming an operating member for the stem of the valve device referred to, which latter is located in, and supported by, the housing 43 and comprises a casing 47 secured at its lower end to the bottom wall of the housing 43 and containing a passage 48 opening through the bottom wall of the cylinder and communicating with the pipe 49 leading from any suitable source of fluid-pressure supply. The side wall of the cylinder 47 contains, above the passage 48 therein, a pair of passages 50 and 51 opening into the interior of the cylinder 47, the passage 50 communicating with the pipe 34. The valve-device now being described also comprises a slide valve 52 located within the cylinder 47 and extending at one side thereof into a groove 53 in the inner wall of the cylinder at the portion thereof in which the passages 50 and 51 are located, the opposite side wall of the

valve 52 being engaged by a spring plunger 54 which operates to press the valve 52 against the side wall of the groove 53, the wall of the valve 52 which opposes the passages 50 and 51, containing a port 55 which is adapted in one position of the valve 52 (the normal raised position shown in Fig. 4), to effect communication between the passages 50 and 51, and when depressed to the position shown in Fig. 5, to extend below the passage 50 but remain in communication with the passage 51. The valve-device also comprises a valve stem 56, shown as vertically reciprocable in the upper portion of the cylinder 47, the stem 56 being provided at its lower end with annular flange portions 57 and 58, the valve member 52 surrounding the portion of the stem 56 between the flange portions 57 and 58, and the opening through the member 52 in which the stem 56 is located, being so proportioned relative to the stem that the space represented at 59 will be provided between the member 52 and the portion of the stem which it surrounds, and the flange portions 57 and 58 being of such size as to cause them to extend in spaced relation, at their peripheries, from the opposing portions of the inner wall of the cylinder 47.

The arrangement and proportions of the parts described, is such, that the fluid-pressure entering the bottom of the cylinder 47 through the pipe 49 holds the valve stem 56, with the parts carried thereby, in raised, normal, position (Fig. 4), in which position the upper end of the valve stem, which engages the under side of the plate member 45, holds the latter in slightly raised position, as shown in Fig. 4; and when the member 45 is depressed by the operator to depress the valve stem 56 and the parts carried thereby, the member 45 will lower the valve member 52 to the position shown in Fig. 5, a lug 100 on the casing 43 serving as a stop for limiting the downward movement of the member 45 in effecting the positioning of the parts as shown in Fig. 5.

A description of the operation of the mechanism shown is as follows:

Assuming the parts of the device to be in the normal position shown in all of the figures of the drawing except Fig. 5, in which position the door sections 15 and 16 are closed, the operator to open the door composed of these sections, bears down on the member 45 with the result of lowering the valve member 52 to the position shown in Fig. 5, whereupon the fluid-pressure flows from the pipe 49 into the interior of the cylinder 47 and thence through the passage 50 to the pipe 34 from which pipe it flows through passage 37^a, past the valve 41 and into passage 38 and 36 and into the cylinder 30 below the piston 29 therein, with the result of raising this piston which causes the

door section 15 to swing upwardly and the door section 16 to swing downwardly, thereby uncovering the fuel-door opening 14 to permit of the stoking of the fire-box. The 5 door remains open, so long as the operator continues to bear down on the member 45, but as soon as he releases pressure on this member, the force of the fluid-pressure entering the cylinder 47 from the pipe 49, 10 raises the valve stem 56, and the parts carried thereby, and also the member 45, to the position shown in Fig. 4, wherein the passage 50 is closed to the incoming fluid-pressure and is caused to be in communication 15 with the exhaust passage 51 through the port 55, whereupon the cylinder 30 becomes vented of the fluid-pressure therein below the piston 29 and the latter, together with the door sections 15 and 16, returns to normal 20 position in which the fuel opening 14 is closed. In the lowering of the piston 29, upon the positioning of the valve-device of Figs. 4 and 5, as just above stated, the fluid-pressure in the cylinder 30 exhausts 25 through both of the passages 31 and 35 from this cylinder, until the piston 29 reaches a position in which its lower end closes communication between the passage 31 and the interior of the cylinder 30, and thereafter 30 the venting of the cylinder is through the passage 35 only. It will be noted that the passage 31 has direct communication, without restriction, with the pipe 34 and therefore the cylinder 30 vents relatively freely, 35 until the piston closes the passage 31. When the venting is confined to the passage 35, a cushioning action on the lower end of the piston 29 is effected, due to the fact that the course taken by the venting fluid-pressure, 40 sure from the passage 35 to the pipe 34 involves a restriction afforded by the needle valve 42, it being understood that the flow of venting fluid-pressure at the lower extremity of the cylinder is through the passage 35, pipe 38, chamber 39, passage 40 and passage 31 to pipe 34.

As shown in the drawings (Figs. 7 and 8) the valve-actuating member 45 is located in the deck 13 in front of and slightly to the left of the center of the opening 14 controlled by the door, the part 45 in the particular arrangement shown being so positioned as to be tread upon by the left foot of the fireman as he turns in right-hand 50 firing to throw the coal from the shovel through the opening 14 into the fire-box. In other words, the automatic opening and closing of the door of the fire-box does not require the fireman to make any other movements than those which he naturally makes in the transferring of the coal from the tender to the fire-box, assuming that the door of the fire-box is constantly open, it being understood that the purpose of providing self-closing door-operating mecha-

nism is to render the door closed during the periods when fuel is not being introduced into the fire-box.

Of course it will be understood that where the fireman fires left-handed, the valve-stem 56 would preferably be so located that he would tread with his right foot upon it in shoveling the coal into the fire-box. However, so far as certain features of my invention are concerned the valve-device of Figs. 4 and 5 may be positioned otherwise than as described, though the described positioning thereof is preferred, and where the conditions render it advisable may be located in the floor of the tender.

While I have illustrated and described a particular construction embodying my invention, I do not wish to be understood as intending to limit it thereto, as the same may be variously modified and altered without departing from the spirit hereof.

What I claim as new, and desire to secure by Letters Patent, is:

1. In combination with a fire-box, a door for its fuel-opening and fluid-pressure-actuated means for operating said door comprising a device operating, when fluid-pressure is supplied thereto, to actuate the door to one position, said door moving to another position when the fluid-pressure is vented therefrom, a pipe for fluid-pressure leading to said device; a valve-device communicating with a source of fluid-pressure and with said pipe and operative to control the flow of fluid-pressure to and from said first referred to device through said pipe comprising a casing containing a port communicating with a supply of fluid-pressure, a second port communicating with said pipe, and a third, exhaust, port, and a slide-valve in said casing having a port which in one position of said valve connects said second and third ports and closes said first named port to said other ports, and when in another position closes said second port to said third port and opens said second port to said first named port, said third port and said port in said slide-valve being out of communication at all times with said first referred to port.

2. In combination with a fire-box, a door for its fuel-opening and fluid-pressure-actuated means for operating said door comprising a device operating, when fluid-pressure is supplied thereto, to actuate the door to one position, said door moving to another position when the fluid-pressure is vented therefrom, a pipe for fluid-pressure leading to said device, a valve-device communicating with a source of fluid-pressure and with said pipe and operative to control the flow of fluid-pressure to and from said first referred to device through said pipe comprising a casing containing a port communicating with a supply of fluid-pressure,

a second port communicating with said pipe, and a third, exhaust, port, and a slide-valve in said casing having a port which in one position of said valve connects said second and third ports and closes said first named port to said other ports, and when in another position closes said second port to said third port and opens said second port to said first named port, said third port and 10 said port in said slide-valve being out of communication at all times with said first referred to port, said valve being so constructed and arranged that the fluid-pressure supplied thereto, through said first named port, operates to move said valve-device to the position in which said second and third ports are in communication.

3. In combination with a fire-box, a door for its fuel-opening and fluid-pressure-actuated means for operating said door comprising a cylinder, a piston operating therein and through the medium of which said door is operated, a passage communicating with a source of fluid-pressure and opening into said cylinder below said piston, said passage containing a check valve opening in the direction of the flow of fluid-pressure to said cylinder, and a passage, having a restriction communicating with said cylinder below said piston and opening into said first named passage.

4. In combination with a fire-box, a door for its fuel-opening and fluid-pressure-actuated means for operating said door comprising a cylinder, a piston operating therein and through the medium of which said door is operated, a passage communicating with a source of fluid-pressure and opening into said cylinder below said piston, said passage containing a check valve opening in the direction of the flow of fluid-pressure to said

cylinder, a passage having a restriction communicating with said cylinder below said piston and opening into said first named passage, and a passage communicating with said first named passage and opening into said cylinder between the extreme positions occupied by said piston in its movement in opposite directions.

5. In combination with a fire-box, a door 50 for its fuel-opening and fluid-pressure-actuated means for operating said door comprising a device operating, when fluid-pressure is supplied thereto, to actuate the door to one position, said door moving to another 55 position when the fluid-pressure is vented therefrom, a pipe for fluid-pressure leading to said device, a valve-device communicating with a source of fluid-pressure and with said pipe and operative to control the flow 60 of fluid-pressure to and from said first referred to device through said pipe comprising a casing containing a port communicating with a supply of fluid-pressure, a second port communicating with said pipe, and a 65 third, exhaust, port, and a slide-valve in said casing and spaced therefrom to provide communication between said first-named port and said second port when said valve is in one position, said valve having a part 70 containing a port which, in one position of said valve, connects said second and third ports and closes said first-named port to said other ports, and when in another position of said valve, closes said second port to said third port, in which condition said first-named port and said second port are in communication, said third port and said port in said slide valve being out of communication at all times with said first-referred-to 75 port.

CHARLES B. ROYAL.
